US00D633162S

(12) **United States Design Patent**
Campanaro et al.

(10) **Patent No.:** US D633,162 S
(45) **Date of Patent:** ** Feb. 22, 2011

(54) **REBOUNDER**

(75) Inventors: **Thomas J. Campanaro**, Rancho Santa Fe, CA (US); **Dan McCutcheon**, San Diego, CA (US)

(73) Assignee: **Engineering Fitness International Corp.**, San Diego, CA (US)

(**) Term: **14 Years**

(21) Appl. No.: **29/343,270**

(22) Filed: **Sep. 10, 2009**

(51) **LOC (9) Cl.** **21-02**

(52) **U.S. Cl.** **D21/797**

(58) **Field of Classification Search** D21/662, D21/672, 694, 780, 797, 814; 482/16, 27, 482/28, 29, 30, 780; 473/219, 431, 434, 473/435, 454

(57) **CLAIM**

The ornamental design for a rebounder, as shown and described.

DESCRIPTION

FIG. 1 is a front perspective view of the rebounder;

FIG. 2 is a rear perspective view of the rebounder;

FIG. 3 is a front elevational view of the rebounder;

FIG. 4 is a rear elevational view of the rebounder;

FIG. 5 is a top plan view of the rebounder;

FIG. 6 is a right side elevational view of the rebounder;

FIG. 7 is a bottom plan view of the rebounder; and,

FIG. 8 is a left side elevational view of the rebounder.

Any broken lines shown in FIGS. 1-8 are included for the purpose of illustrating environmental elements only and form no part of the claimed design.
